Primary Examiner — Terry Wallace*(74) Attorney, Agent, or Firm* — Taylor J. Ross(57) **CLAIM**

The ornamental design for an expanding lid for pastry carrier, as shown and described.

DESCRIPTION

FIG. 1 is a top, front and side perspective view in the collapsed position of the expanding lid for pastry carrier showing my new design;

FIG. 2 is a top, front and side perspective view thereof in the expanded position;

FIG. 3 is a top plan view thereof;

FIG. 4 is a bottom plan view thereof;

FIG. 5 is a front elevation view thereof in the collapsed position, the rear elevation being identical thereto;

FIG. 6 is a front elevation view thereof in the expanded position, the rear elevation being identical thereto;

FIG. 7 is right side elevation view thereof in the collapsed position, the left side elevation being identical thereto;

FIG. 8 is right side elevation view thereof in the expanded position, the left side elevation being identical thereto;

FIG. 9 is a cross-sectional view taken along line 9-9 of FIG. 4 in the collapsed position; and,

FIG. 10 is a cross-sectional view along line 10-10 of FIG. 4 in the expanded position.
